E. J. FALKNER.

RECEPTACLE FILLING AND MEASURING MACHINE FOR LIQUIDS.

FILED MAY 12, 1921.

FIG. 2

UNITED STATES PATENT OFFICE.

EDWARD JOHN FALKINER, OF PADDINGTON, SYDNEY, NEW SOUTH WALES, AUSTRALIA, ASSIGNOR TO THE MULTIPLEX PACKETING AND FILLING MACHINE COMPANY, OF WELLINGTON, NEW ZEALAND, A COMPANY OF NEW ZEALAND.

RECEPTACLE FILLING AND MEASURING MACHINE FOR LIQUIDS.

Application filed May 12, 1921. Serial No. 468,991.

To all whom it may concern:

Be it known that I, EDWARD JOHN FALKINER, a subject of the King of Great Britain and Ireland, residing at Paddington, Sydney, New South Wales, Australia, have invented a new and useful Improvement in Receptacle Filling and Measuring Machines for Liquids; and I do hereby declare the following to be a full, clear, and exact description of the same.

This invention relates to measuring apparatus for rapidly dividing stock quantities of mobile liquids in relatively small quantities of equal volume, such apparatus having its chief utility in warehouses and retail shops for the rapid bottling of stock liquids into uniform volume.

The invention consists in certain structural improvements particularized in the gravity flow type of such machines in which the liquids are measured simultaneously in a plurality of telescopic vessels of adjustable dimensions, and the measured quantities are delivered therefrom directly into bottles.

In the accompanying drawings,

Figure 1, is a plan view, and

Figure 2, is a longitudinal sectional elevation.

Referring to the drawings, the stock liquid is supplied through a main pipe 100 terminating in a head 101, which is set immersed to obviate foaming, into a receiving vessel 102 which is provided with a gauge glass 103. This vessel is set up within the supply cistern 104 and it is fitted with a drop foot valve 105 controllable by a pull lever 106. Liquid in the cistern 104 is maintained at a normal level therein by means of an overflow pipe 107, the lower end of which is a telescopic fit in a delivery pipe 108, fitted with a valve 109 by which it may be opened into the transfer cistern 117. When this valve 109 is opened, liquid contained in the cistern 104 above the top end of the pipe 107 will flow from the cistern 104 into the transfer cistern 117. The valve 109 is controllable by means of a hand lever 119 fixed on its spindle 120, said spindle passing through the bottom of the cistern 117, to enable fitting of the hand lever 119 in an accessible place.

The cistern 104 is mounted on the main table 110 and said table is carried on studs

or stanchions 111 mounted on a base 112; 55 the measuring devices, and certain other apparatus hereinafter described, including the sleeve 108 and the valve 109, are contained in a cistern 117 which is carried on a table 113, which is movable by jack screws 114, all of which are geared to a shaft 115 fitted with a hand wheel 116 by operating which the table 113 may be raised or lowered as required. 121 is a displacing vessel. It is a cylinder carried on a lever arm 122 65 which is provided with a fixing device 123 by which its vertical position may be controlled. The displacing cylinder 121 is guided on a post 124 which is a free sliding fit through its tubular centre. 125 are 70 measuring vessels, of which there may be any required number. The capacity of each of these vessels is determined by the adjustment of the tubular ended conical heads 126 which are fixed on the depending tubular studs 127, said studs being screwed up to the table 110 so as to permit individual adjustment of the capacities of the vessels 125. 128 are air evacuating holes in the tops of the tubular studs 127. The conical 80 heads 126 are fitted with piston rings (not shown) to form a liquid tight fit in the vessels 125. These piston heads are fitted with two air evacuating devices; firstly, a central tube 129 for which clearance is provided within the tubular studs 127, and secondly a lateral tube 130 connected into a vent hole 131 leading to a flute or groove 132 on the side of the cone face of the piston head. The lower ends of the chambers 85 125 are conical as shown at 133 and lead into necks 134 which are screw mounted in a socket 135 on the bottom of the cistern 117. Screwed up in this socket is also the reduced portion 136 of the control valve 90 casing 137. The chambers 125 are filled through the inflow pipes 140, 141 being angularly disposed sockets having a closure plug 142 at their ends to facilitate insertion of cleaning means into the passageway. 95 The valves 144 are slotted through between their cheeks which are neatly contained in pockets in the casings 137, but a sector portion 153, sufficient to close the necks 134, is left. The outlet necks of the valve casings 100 137 are provided with spouts 146 adapted to direct measured liquid into bottles 147 located on a tray 148, preferably slidably

mounted on a table 149 fixed on the base structure. The valves 144 are connected by their crank arms 150 to links 151 and are operatable as a gang by moving said links 5 by pushing or pulling on the hand grips 152.

The method of operation is as follows:— The table 113 having been adjusted for position so as to bring the piston heads 126 into proper vertical position in the chambers 125 10 so that the clearance space will contain the precise quantity of liquid required to be delivered at each operation, liquid is supplied to the receiving vessel 102 through the pipe 100. The valve 105 is lifted by operating 15 the lever 106 to allow liquid to flow from the vessel 102 into a cistern 104. The valve 105 is then closed, and the valve 109 opened by means of its lever 119. The overplus of 20 the liquid above the top end of the pipe 107 flows down through said pipe and through the pipe 108 and is passed by the valve 109 into the transfer cistern 117 which is normally kept filled to the top level of the pipes 140. The liquid overflowing into the pipes 25 140 fills the measuring vessels 132 and then rises above pipes 140. The valve 109 is then closed and the displacing vessel 121 is raised, with the result that the surface level of the liquid in the transfer cistern 117 is caused 30 to drop below the mouths of the intake pipes 140. Air displaced from the vessels 125 finds its way out through the air pipe 129 and the lateral air duct and air pipe 130, so that the whole of the clearance space in the 35 vessel becomes quite filled with liquid. The valves 144 being now operated by forcing over the gang links 151, the liquid so measured flows through the spouts 146 into the bottles 147. On completion of delivery the 40 valves 144 are closed by the reverse movement, the displacing vessel is again lowered and the same operations are repeated.

What I claim is:

1. Liquid measuring apparatus comprising 45 a stock cistern on a fixed table, a vertical movable table below the same with inter-geared jack screws for altering its vertical location, a charging cistern on said movable table a valved telescopic pipe for discharging liquid from the stock cistern into the charging cistern, means to operate the valve from outside the charging cistern, a displacing device carried on a lever adapted 50 for altering the surface level in said charging cistern, measuring vessels within the 55

charging cistern having their lower ends fitted through the bottom of said cistern, stand pipes adapted to flow liquid into said vessels when the liquid level in said charging cistern is above said pipes, coned heads 60 carried pendently by the fixed table and in said vessels as the table levels are relatively altered to vary the measuring gauge, and air vents disposed centrally and laterally 65 through said heads.

2. Liquid measuring apparatus comprising 70 a fixed and a vertically movable table, a stock cistern and a charging cistern carried respectively on said tables, measuring vessels within the charging cistern having outlets fitted through the bottom of said cistern, 75 gang valves below the adjustable table controlling the several measuring vessel outlets, telescoping liquid transferring means between the cisterns with a valve within the charging cistern at the lower end of the lower section and having such section fixed to the charging cistern, means external to the charging cistern for operating said valve, liquid displacing means 80 in the charging cistern, and air vented adjustable slide heads carried by the fixed table and extending into the measuring vessels.

3. In liquid measuring apparatus of the type herein described, the combination of a 85 receiving vessel into which stock liquid may flow through a pipe terminating near the bottom thereof, a lift valve for passing liquid from said vessel into a supply cistern enclosing the receiving vessel, a valve telescopic pipe adapted to pass liquid from said supply cistern to a transfer cistern below it, a plurality of measuring vessels in said transfer cistern with valved outlets passing 90 through the bottom thereof, conical heads 95 telescopicly slidable in said vessels by varying the vertical position of said transfer cistern relatively to said supply cistern, stand pipe fillers for said measuring vessels, and a liquid displacing vessel mounted on a lever for altering the surface level of liquid in said transfer cistern.

In testimony whereof, I have signed my name to this specification in the presence of two subscribing witnesses.

EDWARD JOHN FALKINER.
